MASON'S IMPLEMENT

Nathan C. Darling, Shelton, Conn., and Chester
A. Darling, McClellan Field, Calif.

Application July 15, 1943, Serial No. 494,860

1 Claim. (Cl. 72—128)

This invention relates to implements employed in the erection of masonry and concrete structures and the like, and more particularly to a combined gravity-flow plastic container and associated spreader guide and gage, broadly termed a trowel, in the specification and claim, which may be employed to spread ribbons of mortar on brick or block courses.

An important object of the invention is to provide such an implement, which supplies a ribbon of plastic of a uniform thickness and width.

Another important object is to provide a trowel or implement of this kind, which supplies a ribbon of plastic with the vertical sides of the ribbon spaced a uniform distance from the planes of the vertical sides or faces of the bricks, blocks or the like.

Still another object is to provide a valved container for plastic (such as mortar), and an associated channeled guide and gage carried by the container and disposed below the valve, with a passageway to the guide when the valve is unseated.

Another important object is to provide a mortar spreader which will minimize waste of the plastic and save time in spreading it, as compared with conventional hand trowel-spreading.

Yet another object is to provide a valved container for mortar and an associated guide and spreader, which may be wholly manipulated by one hand of the mason.

Still another object is to provide such an implement wherein the operator will be aware at all times of the quantity of plastic within the container.

Other objects and advantages of this invention will be apparent during the course of the following detailed description of the invention, taken in connection with the accompanying drawing, forming a part of this specification and in which drawing:

Figure 1 is a side elevation of the novel implement.

Figure 2 is a vertical section of the implement, illustrated as discharging mortar upon a concrete block, shown in fragmentary vertical section.

Figure 3 is a bottom plan of the novel trowel or implement.

Figure 4 is a perspective view, showing ribbons of mortar being spread along the upper faces of a course of concrete blocks.

In the drawing, wherein for the purpose of illustration is shown a preferred embodiment of the invention and wherein similar reference characters designate corresponding parts throughout

the several views, the letter A may designate the novel implement, the letter B a plastic adapted to be spread out into a ribbon and C material, such as bricks or concrete blocks, being cemented together with the plastic B.

The novel implement preferably comprises a plastic spreader and guide means 10, means for conducting plastic to the spreader and guide means 10, which may be a container or reservoir 11, handle means 12 to move the implement along the course, and valve means 13, between the container or the reservoir 11 and spreader and guide means 10.

As for the spreader and guide means 10, the same comprises an inverted, elongated, channel shaped member 15, having opposite side walls 16 and 17, the first being termed the outer side wall and the latter the inner side wall. The outer side wall 16 is deeper than the side wall 17, as shown particularly in Figure 2, and is provided with a substantially flat face 18, with the lower portion of this face 18 adapted to slide along the upper portions of the side walls of conventional bricks and building blocks. The side wall 17 has a substantially flat lower edge 19, adapted to slide over a portion of the upper faces of these bricks or blocks. An upper or top, horizontally disposed substantially flat wall 20 joins the walls 16 and 17 and is provided with an opening or passageway 21, somewhat oval in shape, as shown in Figure 3, preferably disposed intermediate the ends of the member 15. The member 15 is free of end walls, so that there is provided an elongated passageway 22 through the member 15, in communication with the passageway 21 and of an area greater than the area of the passageway 21.

Preferably disposed directly over the member 15 is the container or reservoir 16, somewhat funnel-shaped, as in Figures 1 and 2, having an open upper mouth 25, side walls 26 and end walls 27 with the walls converging downwardly to meet the wall 20 at the passageway 21. The lowermost portions of the inner faces of these walls 26 and 27 provide a valve seat 28. The reservoir 16 is preferably what the word implies—a container for a considerable supply of material, which may be drawn upon to supply measured volumes of material to the means 10, and is not, primarily, a container such as a conventional trowel for a small volume of material. In fact, in practice, it has been found feasible to provide a container of a 12 quart capacity. The means 10 and 11 may be integral or may be separate parts joined together as by welding. Since some plastics, such as mortar, are inclined to adhere to the walls of

a container, a suitable oil, as thin waste engine oil 28, may be applied to the walls 26 and 27.

The handle means 12 is shown as comprising a substantial straight, round rod 30, bridging the mouth 25 of the reservoir 16, having a head 31 at one end and any suitable means, such as a pin 32 at the other end, with the rod 30 secured in suitable openings in a pair of ears 33 extending upwardly above the mouth 25 from opposite sides of reservoir 16. This handle may be grasped as 10 suits the operator, one way being shown in Figure 4, for moving the implement along a course. This rod 30 has a dual function as will be next explained.

Valve means 13 preferably comprising a valve 35, shaped to seat upon the valve seat 28, and a valve stem 36 which extends upwardly from the valve 35, through the reservoir 16, and may comprise a length of suitable material having some resiliency so that while it may be shaped at its upper end to provide the two spaced-apart, semi-circular handle-engaging portions 37 and 38, shown in Figure 2, the extremity 38 will have a tendency to spring toward the facing portion of the stem. When the portion 37 is about the rod 30 (as shown in dot-and-dashes) the valve 35 is seated and when the portion 38 is about the rod 30 (as shown in full lines in Figure 2) the valve is unseated, and plastic material may flow through the passageway 21, until the operator disengages the portion 38 from the rod 30, whereupon suction created by the flowing plastic B will draw the valve 35 to a seated position and the portion 37 will then engage the rod 30.

Operation of the novel implement is by hand. After the reservoir 16 is suitably coated as described, and the valve 35 is seated, a volume of plastic B, as mortar, is poured into the reservoir 16. When a course of the material C, such as hollow concrete building blocks 40 is laid, the operator lifts the implement, by the rod handle 30 and sets it upon the upper face 41 of a suitable block, with the inner face 18 of the elongated side wall 16 of the spreader and guide means 10, in

contact with the upper portion of one side face 42 of the block 40. When the valve 35 is unseated, as by drawing up on the valve stem 36, the plastic B will flow through the passageway 21 and into the passageway 22 and fill it. Upon moving the implement along the course, guided by the elongated side wall 16 in contact with the faces 42 of the blocks 40, uniform ribbons 43 of mortar will be spread along the upper faces 41 of the blocks 40 ready to receive the next course of blocks. It will be noted that the ribbons 43 are so disposed that material will not be wasted, as by dropping into the hollows 44 of the blocks 40, there is a neat, outer edge of mortar, uniform in thickness, and with this edge paralleling the vertical planes of the adjacent side faces 42 of the blocks, and all this is accomplished rapidly, with the operator, looking down upon the work and container, able to ascertain at all times the volume of plastic B in the open-mouthed reservoir.

Various changes may be made to the form of the invention, herein shown and described, without departing from the spirit of the invention or scope of the following claim.

What is claimed is:

A trowel adapted to form ribbons of mortar along the upper faces of bricks, blocks and the like, comprising a reservoir, having an open, upwardly-extending mouth and an exit at its lower end; a handle bridging said mouth with the vertical longitudinal plane of said handle substantially bisecting said reservoir, said handle being secured at adjacent its ends to said reservoir; and a valve for said exit, having a stem extending upwardly through said reservoir to said handle and provided with means to suspend said stem from said handle at selected distances above said first-named passageway, said last-named means including a resilient U-shaped arm having a pair of handle-engaging sections, shaped to conform to a portion of the transverse cross-section of said handle.
